RAILWAY TRUCK

Donald S. Barrows, Rochester, N. Y., assignor to
The Symington-Gould Corporation, Rochester,
N. Y., a corporation of Maryland.

Original application June 14, 1932, Serial No.
617,228, now Patent No. 2,146,200, dated Feb-
ruary 7, 1939. Divided and this application
February 5, 1938, Serial No. 188,972

7 Claims. (Cl. 105—197.1)

This is a divisional application of my pending application Serial No. 617,228, filed June 14, 1932, entitled Railway truck, which has matured into Patent No. 2,146,200, granted February 7, 1939. This invention relates to railway trucks and more particularly to the construction and arrangement of the side frames, bolster and associated spring means.

One of the objects of the present invention is the provision of a railway truck in which the bolster is supported from spaced associated side frames by means of nests of springs which include helical or coil springs and leaf or elliptic springs, the elliptic springs being relatively taller than the helical springs and the bolster ends being arranged to accommodate the parts of the elliptic spring which extend above the helical springs.

Another object of the invention is the provision, in a railway truck, of helical and elliptic springs associated with each end of a bolster and corresponding side frames, some of the said springs being disposed at an angle to the horizontal so as to cushion the transverse movement of the bolster, thereby providing absorbing means for lateral forces.

A further object of the invention is the provision, in a railway truck, of helical and elliptic springs interposed between an associated bolster and spring plate, both of which are provided with substantially horizontal helical spring seats and an elliptic spring seat disposed at an angle to the helical spring seats, the elliptic spring seats being provided with cylindrically curved surfaces so as to allow for an equalization of the elliptic spring with respect to the associated parts thereof.

These and other objects will become apparent from the following description and by referring to the accompanying sheet of drawings which exemplifies an embodiment of the invention.

Generally considered, the drawing illustrates in

Figure 1 a partial side elevation of a railway truck, a portion of which is shown in vertical section so as to more clearly illustrate the structure, and in

Figure 2 a vertical sectional view taken along the lines 2—2 of Figure 1 and looking in the direction of the arrows.

Referring now to the drawing in detail, wherein like parts are designated by like reference characters, there is shown a railway truck preferably of the spring plankless type and comprising a pair of spaced side frames 2^c only

one of which is fragmentarily shown. Each of the side frames 2^c includes a compression member 3 spaced above a tension member 4^c and longitudinally spaced vertically extending guide columns 5 which connect intermediate portions of the compression and tension member to form a window or bolster opening 6 therebetween. The portion of the tension member 4^c intermediate the guide columns is preferably box-shaped in transverse cross section and comprises an upper web 7^c forming a spring plate seat portion, a lower web 8 spaced below the upper web 7^c, and vertical side flanges 9 which extend between and integrally join the upper and lower webs 7^c and 8 respectively. The upper web 7^c laterally of the side flanges 9 is extended inwardly and outwardly of the side frame beyond the said flanges, as at 10, to thereby increase the bearing area of the tension member and form an adequate support for the superimposed spring plate 11.

The junctions between the tension member 4^c and the guide columns are preferably reinforced or strengthened by means of longitudinally spaced convoluted or embossed portions 12 which extend longitudinally of the side frame and are upstanding from the tension member. The convoluted or embossed portions 12 form triangular gussets which preferably start adjacent the vertical transverse plane of the truck structure 30 and extend diagonally outward therefrom to intersect the column guides above the plane of the upper web 7^c and continue toward the end of the tension member in a manner similar to that disclosed and claimed in my prior Patent No. 1,652,808, dated December 13, 1927. This construction not only obviates the necessity of providing squaring or spring-retaining lugs on the upper web 7^c of the tension member but also permits an interlocking means for the spring plate 11, thereby retaining the plate in operable position. In order to accomplish this latter result, the spring plate 11, which includes a main web 11^a, is provided with side longitudinally directed convolutions or embossments 13 each of which is directed outwardly toward the adjacent guide column and nests over the corresponding convolution 12 formed on the tension member.

A load-carrying member or bolster 14, extending between and connecting the side frames, has an end portion 15 thereof positioned in the upper area of each window opening 6 in vertically spaced relation to the upper web 7^c of the tension member. Each bolster end prefer-

ably comprises a top web 16 and a bottom web 17 integrally connected adjacent their free edges by spaced vertical side walls 18, the latter of which are closely associated with the guide 5 columns 5 of the side frame and thereby limit the movement of the bolster with respect to the side frame longitudinally of the truck structure. Extending outwardly of the bolster side walls 18 adjacent each bolster end are inner and outer 10 lugs 19 which embrace and are adapted to engage the corresponding guide columns.

In the present embodiment the load-carrying member or bolster 14 is resiliently supported by means of a nest of springs including an elliptic 15 spring 20 comprising two groups or banks of vertically spaced curved plates 20^a spaced at their respective ends by castings or members 20^b and retained in assembled relation by means of upper and lower intermediate bands 21^c and 20 22^c respectively. The elliptic spring 20 is desirably positioned centrally of the spring group and extends in a transverse direction with respect to the truck structure. Spaced on either 25 side of the elliptic spring is a pair of coil or helical springs 23^c, each of which is preferably disposed on either side of the convoluted portions 12 and 18 of the tension member and spring plate respectively.

In order to provide an arrangement in which 30 the elliptic spring plates 20^a will not be flexed beyond the point of contraflexure, even when the helical springs 23^c are fully compressed upon a complete downward movement of the bolster, the elliptic spring is desirably formed taller than the helical springs with the excess height thereof extending into a downwardly opening pocket or recess 27^c in the bolster. The recess 27^c is preferably formed by convoluting the bottom web 17 of the bolster so that the upper web 28^c defining the upper extremity of the pocket may be inclined, as at 29, and thereby permit the inclined portion 29 to overlie the upper inner contour of the upper plates 20^a in spaced relation and with an approximately uniform clearance therebetween. Each bolster end 15 is preferably reinforced by means of vertically disposed spaced gussets 30 which extend between the upper web 28^c of the convoluted portion and the top web 16 of the bolster.

In order to cushion lateral thrusts or side shocks 50 of the bolster and thereby impart a smoother lateral motion to the bolster, the elliptic spring is inclined to a horizontal plane with its outer end normally disposed at a higher elevation than its inner end. By thus disposing the major axis of the elliptic spring at an oblique angle to the horizontal the spring may be made longer than normal on account of the external truck clearance line becoming wider as the distance from the top of the rail increases, which will permit a corresponding increased length of the elliptic spring when it is raised from normal position above the rails. When the elliptic spring is disposed in a sloping or inclined position, as illustrated, it is 55 adapted to directly cushion a certain amount of transverse movement of the bolster which results in lateral forces being imparted thereto. Any lateral movement of the bolster permitted by the clearance between the guide column and bolster lugs 19 will compress the elliptic spring an amount determined by the angle of inclination of the elliptic spring so that a positive absorbing or cushioning means is provided for lateral forces.

The upper elliptic spring band 21^c is in bearing

relation with a boss forming spring seat 31 which is downwardly facing and provided on the upper web 28^c of the bolster convoluted portion 27^c, while the lower elliptic spring band 22^c is in bearing relation with an intermediate convoluted portion 32 which is upwardly facing and formed on the spring plate centrally thereof. The spring seat 31 and intermediate convoluted portion 32 are desirably disposed at oblique angles to a horizontal plane so as to correspond substantially with the angle of inclination of the major axis of the elliptic spring and thereby provide a full bearing area between the elliptic spring bands 21^c and 22^c and their associated seats on the bolster end and spring plate.

In order to allow for the equilibration of the elliptic spring with respect to the bolster and spring plate as the bolster moves transversely of the truck structure, the upper and lower intermediate bands 21^c and 22^c are each provided with outer cylindrical convex surfaces 50 and 51 respectively. The convex surface 51 of the lower band is in bearing relation with a cylindrical concave surface 49 formed on the intermediate convoluted portion 32 of the spring plate, while the convex surface 50 of the upper band bears directly against a cylindrical concave surface 52 formed on the spring seat 31 of the bolster. It is not the present intention to limit the radii of the convex surfaces to any particular dimension as 30 it will be clearly understood that these surfaces may be formed coaxial and about an axis midway therebetween so as to provide for a free plane horizontal movement of the bolster with respect to the side frame. Both of the elliptic spring 35 seats 31 and 32 are defined by spaced ribs 33 which lie adjacent and are adapted to engage the corresponding spring band, thereby preventing an accidental or unwarranted shifting of the elliptic spring laterally of the truck structure.

Spaced on either side of the bolster convoluted portion 21^c are substantially horizontal helical spring seats 34 which have lugs 35 projecting downwardly therefrom. The lugs 35 extend into the upper portion of the helical springs and form 45 retention means for preventing the accidental displacement of the helical springs. The main web of the spring plate is provided with a substantially horizontal surface 36 which forms helical spring seats on opposite sides of the intermediate 50 convoluted portion 13 and has upstanding therefrom positioning lugs 37 adapted to extend into and interlock with the lower extremity of the helical springs 23^c. Top spring plates 53 are desirably provided between the helical spring seats 34 of the bolster and the upper bearing portion of the helical springs, but these plates are not essential, as will be understood, and may be dispensed with.

It will be appreciated that merely an exemplary 60 form of the present invention has been disclosed and described and further, that numerous alterations may be made within the spirit and scope of the appended claims.

I claim:

1. In a railway truck, in combination, a side frame formed with compression and tension members spaced intermediate their ends by spaced columns to leave a bolster opening therebetween, a spring plate on said tension member, a bolster 70 having an end portion thereof positioned in said opening and provided with lugs outstanding from the sides thereof engaging said columns, said bolster end and spring plate being provided with helical and elliptic spring seats, helical and el- 75

5 elliptic spring means in bearing relation with said spring seats and interposed between said bolster end and spring plate for resiliently supporting the bolster, said helical springs being vertically disposed and said elliptic spring having its major axis extending at an oblique angle to the horizontal.

10 2. In a railway truck, in combination, a pair of side frames each formed with compression and tension members spaced at intermediate portions by spaced column members to form a window opening therebetween, a bolster with its end portions extending into said window openings and provided with lugs engaging said column members, a pair of upright helical springs interposed between each of the tension members and bolster ends and spaced on either side of the vertical transverse plane of the truck, and an elliptic spring positioned in the vertical transverse plane 15 of the truck and interposed between each of said tension members and bolster ends, each of said elliptic springs having its major axis extending at an oblique angle to the horizontal.

20 3. In a railway truck, in combination, a side frame including vertically spaced compression and tension members joined intermediate their ends by spaced guide columns to form a bolster opening therebetween, a bolster with its end portion received in said window opening, means 25 on said bolster for engaging the guide columns, helical and elliptic spring means interposed between the said tension member and bolster end for resiliently supporting the bolster, said bolster end having substantially horizontal helical spring 30 seats and an elliptic spring seat disposed at an oblique angle to the helical spring seats, the helical springs being substantially upright and the elliptic spring having its major axis extending at an oblique angle to the horizontal.

35 4. A bolster having an end portion adapted to 40 occupy a correspondingly formed opening in an

associated side frame, substantially horizontal helical spring seats on said bolster end spaced on either side of the vertical longitudinal plane of said bolster, and an elliptic spring seat on said bolster end positioned in said longitudinal plane, 5 said elliptic spring seat extending at an oblique angle to the helical spring seats in order to permit the major axis of an associated elliptic spring to extend at an oblique angle to the horizontal.

10 5. A spring plate for a truck spring unit comprising elliptic and helical springs including a web having a plane surface forming helical spring seats and a convoluted portion forming an elliptic spring seat, said convoluted portion having a cylindrically curved surface angularly disposed to the helical spring seats so as to position the major axis of the elliptic spring at an oblique angle to the horizontal. 15

15 6. A spring plate for a truck spring unit comprising elliptic and helical springs, said plate 20 including a web having oppositely disposed side convoluted portions adapted to nest over correspondingly formed convolutions on an associated side frame, a plane surface on said web forming helical spring seats, and an intermediate convoluted portion forming an elliptic spring seat, said intermediate convoluted portion being angularly disposed to the helical spring seats so as to 25 position the major axis of said elliptic spring at an oblique angle to the horizontal. 30

25 7. A spring plate for a truck spring unit comprising a web having side convoluted portions adapted to nest over correspondingly formed convolutions on an associated side frame, a spring seat formed on said web, said spring seat being 35 disposed at an oblique angle to said web, and means associated with said spring seat for retaining an associated spring in a predetermined position. 35
